UNITED STATES PATENT OFFICE.

ROSWELL H. RAUSCH AND NICHOLAS MARCALUS, OF PLAINFIELD, NEW JERSEY, ASSIGNEES TO NILES-BEMENT-POND COMPANY, OF NEW YORK, N. Y., A CORPORATION OF NEW JERSEY.

MACHINE-TOOL-FRAME STRUCTURE.

Application filed November 5, 1923. Serial No. 672,942.

To all whom it may concern:

Be it known that we, ROSWELL H. RAUSCH and NICHOLAS MARCALUS, citizens of the United States, residing at Plainfield, in the county of Union and State of New Jersey, have invented certain new and useful Improvements in Machine-Tool-Frame Structures, of which the following is a specification.

10 This invention relates to boring mills, planers and like machines wherein a tool supporting cross rail is mounted on a pair of uprights adjacent and extending above a work supporting table. The cross rail spans 15 the uprights and is ordinarily adjustable vertically thereon, the rail being ordinarily supported entirely by the uprights. When performing very heavy cutting operations, the portion of the rail intermediate the uprights 20 is liable to spring or vibrate. To prevent such occurrence, we provide an abutment between the uprights, preferably integral therewith, for rigidly backing up such portion of the rail. As illustrated in the drawings, we 25 provide each upright with an inwardly extending bracket-like projection and bolt such projections together at their junction. The cross rail has a rearwardly extending portion which engages against an abutment 30 surface of these brackets. The primary object of the invention is to provide an improved machine tool structure of this type.

As illustrated in the drawings, the two uprights are constructed independently and 35 thereafter assembled by bolting the bracket portions together. Such construction can be very readily manufactured and when assembled forms a very rigid frame. Means is provided in connection with the rail and 40 brackets for preventing looseness therebetween. Such means can be of any construction desired, three of such means being illustrated in the drawings. Another object of the invention is to provide an improved 45 machine tool structure of the type described which can be readily and cheaply manufactured and which will adequately and substantially perform the functions stated.

With the above and other objects in view, 50 our invention consists in the features of construction and operation set forth in the following specification and illustrated in the accompanying drawings. In such drawings annexed hereto and forming a part of this

specification, we have shown certain embodiments of our invention in a planer but it will be understood that the invention can be otherwise embodied and that the drawings are not to be construed as defining or limiting the scope of the invention, the claims appended to this specification being relied upon for that purpose.

Referring to the figures of the drawings:

Figure 1 is a fragmentary plan view of a planer embodying our invention.

Fig. 2 is a front elevation thereof, the cross rail being shown in dot and dash lines.

Fig. 3 is a fragmentary plan view of a modified form of the invention.

Fig. 4 is a fragmentary sectional view 70 thereof taken on line 4-4 of Fig. 3.

Fig. 5 is a rear elevation of another modified form of the invention.

Fig. 6 is a sectional view thereof taken on line 6-6 of Fig. 5.

Fig. 7 is a sectional view taken on line 7-7 of Fig. 5.

Referring more specifically to the drawings by reference characters, 1 indicates the bed of a planer on the horizontal ways 2 of 80 which is slidably mounted a work table 3. A pair of uprights 4 are secured rigidly to the opposite sides of the bed and extend upwardly above the table. The front portions of the uprights are faced off at 5 and a tool 85 supporting cross rail 6 is slidably mounted thereon. Blocks 7 are bolted to the rail and engage the uprights in a manner to hold the rail in place thereon.

Projecting inwardly from each upright 4 90 is a bracket 8 preferably integral with the uprights as illustrated. Each bracket comprises a front vertically extending body portion 8^a, a vertical rearwardly extending portion 8^b, and a horizontal rearwardly extending reinforcing rib 8^c. When assembled the portions 8^b are adjacent each other and are bolted together at 9 with a filler 10 therebetween. The filler is of comparatively soft material and the function thereof is to provide a secure jointure of the brackets without requiring any accurate fitting between the adjacent faces of the portions 8^b.

The portion of the cross rail between the uprights extends rearwardly at 11 and, as 105 shown in Figs. 1, 2, 5, 6 and 7, the rear vertical surface thereof is faced off at 12 to engage a like vertical front surface on the por-

tion 8^a of the brackets. Any suitable means can be provided for drawing these vertical surfaces into firm engagement.

As illustrated in Figs. 1 and 2, the portion 5 11 of the cross rail is provided with two vertically extending T-slots 13 adapted to receive the heads of bolts 14 mounted in the portions 8^a of the brackets 8. The cross rail can be vertically adjusted on the uprights 10 and thereafter secured in place by rotating the nuts 14^a.

As illustrated in Figs. 5, 6 and 7, each bracket 8 is provided with two holes 15 and 16 therein. A clamping bolt 17 can extend 15 through the hole 15 and engage in any one of three tapped holes 18 in the cross rail or the bolt can be placed in the hole 16 and engage in any one of two tap holes 19 in the cross rail. It should be noted that the 20 holes 15 and 16 are slightly larger than the bolt 17 whereby to provide for a slight vertical adjustment of the rail. Also the through holes 15 and 16 and the tapped holes 18 and 19 are alternately arranged in 25 a manner to provide vertical adjustment of the rail on the uprights. The arrangement of the holes 15 and 16 and holes 18 and 19 in combination with the oversize feature of the holes 15 and 16, relative to the bolts 17, 30 permits fine adjustment of the rail to any position desired between the upper and lower limits of adjustment. It will of course be understood that as many holes 15, 16, 18 and 19 can be provided as desired.

35 In Figs. 3 and 4, the cross rail is not positively connected to the brackets 8 but adjustable means in connection therewith are adapted to provide a rigid bearing between such members. The brackets are 40 faced off at 20 in a manner to cooperate with surfaces on the rail faced off at 21. A pair of taper gibs 22 are provided between these surfaces, the gibs being adjustable longitudinally by means of screws 23 threaded into 45 the rail. It will be readily understood that by adjusting the gibs downwardly, the gibs wedge into place between the surfaces in a manner providing a rigid bearing between the rail and brackets.

50 What we claim is:

1. In a machine tool, the combination of a base, a pair of spaced uprights thereon, a bracket projecting inwardly from each upright toward the other upright, means detachably securing the brackets together, and a cross rail mounted to slide vertically on the uprights, the portion of the rail between the uprights being supported rearwardly by bearing against the said brackets.

60 2. In a machine tool, the combination of a base, a pair of spaced uprights thereon, a bracket projecting inwardly from each upright toward the other upright, means for securing the brackets together, and a cross rail mounted to slide vertically on the up-

rights, the cross rail having a rearwardly extending portion intermediate the uprights in engagement with the said brackets.

3. In a machine tool, the combination of a base, a pair of spaced uprights thereon, each upright being provided with an integral bracket projecting toward the other upright, means securing the said brackets together, a cross rail mounted to slide vertically on the uprights, the cross rail having a rearwardly extending portion intermediate the uprights in engagement with the said brackets, and means preventing looseness between the rail and the said brackets.

4. In a machine tool, the combination of a base, a pair of spaced uprights thereon, each upright being provided with an integral bracket projecting toward the other upright, a filler between the said brackets, bolts for securely connecting the brackets together with the filler therebetween, and a cross rail mounted to slide vertically on the uprights, the portion of the rail between the uprights being supported rearwardly by bearing against the said brackets.

5. In a machine tool, the combination of a base, a pair of spaced uprights thereon, a bracket projecting inwardly from each upright toward the other upright, means for securing the brackets together, a cross rail mounted to slide vertically on the uprights, the cross rail having a rearwardly extending portion intermediate the uprights in engagement with the said brackets, the engaging surfaces of the brackets and cross rail being faced off to provide cooperating bearing surfaces therebetween, and means providing a rigid bearing between the cross rail and brackets with the rail in any one of various positions of vertical adjustment.

6. In a machine tool, the combination of a base, a pair of spaced uprights thereon, each upright being provided with an integral bracket projecting toward the other upright, each bracket comprising a vertically extending body portion and a horizontally extending reinforcing rib, means securing the said brackets together, and a cross rail mounted to slide vertically on the uprights, the cross rail having a rearwardly extending portion intermediate the uprights in engagement with the said vertically extending body portions of the brackets.

7. In a machine tool, the combination of a base, a pair of spaced uprights thereon, a cross rail mounted to slide vertically on the uprights, a bracket projecting inwardly from each upright toward the other upright, each bracket comprising a vertical body portion parallel with the rail, a vertical portion at right angles thereto and a horizontally extending reinforcing rib integral with both said portions, the second named vertical portions being adjacent and parallel, and means for securing such portions to-

gether, the cross rail having a rearwardly extending portion intermediate the uprights in engagement with the first mentioned vertical portions of the brackets.

5 8. In a machine tool, the combination of a base, a pair of spaced uprights thereon, a bracket projecting inwardly from each upright toward the other upright, means for securing the brackets together, a cross rail 10 mounted to slide vertically on the uprights,

the portion of the rail between the uprights being supported rearwardly by bearing against the said brackets, and adjustable means providing a rigid bearing between the cross rail and brackets. 15

In testimony whereof, we hereto affix our signatures.

ROSWELL H. RAUSCH.
NICHOLAS MARCALUS.
